UNITED STATES PATENT OFFICE

CHARLES O. REEPS, DECEASED, LATE OF WAUKEGAN, ILLINOIS, BY HARRIETTE ESTELLE REEPS, EXECUTRIX, OF WAUKEGAN, ILLINOIS, ASSIGNOR TO NATIONAL LAUNDRY MACHINERY COMPANY, INC., OF SYRACUSE, NEW YORK, A CORPORATION OF DELAWARE

SLEEVE PRESS

Application filed January 2, 1930, Serial No. 418,117. Renewed May 12, 1932.

This invention relates to ironing presses particularly to presses for ironing parts of garments such for example as the sleeves of men's shirts.

5 In the copending application of Charles O. Reeps, Serial No. 386,339, filed August 16, 1929, is disclosed a press in which a stationary buck and a swingable ironing head are heated, together with means for circulating 10 air through the buck to deflect upwardly or balloon the upper layers of the buck padding into pressure engagement with the article to be ironed so that the article is subjected to the application of hot, dry air to be thoroughly 15 aerated and quickly dried, and is applied with uniform yieldable pressure against the hot ironing head.

An important object of the present invention is to produce a machine having the same 20 general construction, operation, and control as the machine in the copending application referred to and which can be used for ironing the general run of articles, but which is provided with a buck structure arranged to be adjusted relative to the ironing head so that garment parts, as for example, shirt sleeves, may 25 be accurately aligned and ironed independently of the other parts of the garment.

Another important object is to provide an 30 arrangement for maintaining connection of the buck structure in the heating and air circulating systems during the entire range of adjustment, so that the article or articles put in the press may be subjected, for any position 35 of the buck structure, to the aerating and drying operation as well as to the ordinary ironing operation.

A further object is to provide a simple 40 means for assisting in the accurate securing and alignment on the buck structure of the garment part to be ironed.

Another object is to provide a simplified 45 arrangement whereby the buck structure, after the application of a garment part thereon, may be readily shifted laterally on the press bed to bring a garment part into accurate position for receiving the ironing head, while at the same time automatically maintaining the buck structure in connection with 50 the heating and air circulating systems.

The above enumerated and other important features of the invention will be fully understood from the following detailed description and the structure disclosed on the drawings, in which drawings:

55

Figure 1 is a front elevation of the press with the ironing head in its normal upper position;

60

Figure 2 is a side elevation, partly in section on line II—II of Figure 1, and showing the ironing head in its lowermost or ironing position;

65

Figure 3 is a front elevation with parts of the buck structure in longitudinal vertical section;

70

Figure 4 is an enlarged vertical section of the upper part of the machine frame and the buck structure and air circulating structure;

Figure 5 is an end elevation of the buck structure;

75

Figure 6 is an enlarged under side view of the adjustable buck structure;

Figure 7 is a side elevation of the buck, the ironing head, and the ironing head supporting frame, in position for the aerating or ballooning operation; and

80

Figure 8 is an enlarged section of a corner of the buck body showing the arrangement of the padding in ballooning position.

The machine shown comprises the support- 85

ing frame 10 having the horizontal top 11 on which is mounted the bed plate 12 of the buck structure. Rising from the bed plate 12 are front and rear guide flanges 13 and 14 presenting parallel guide channels 15 and 16

86

for receiving the sides of the rectangular base 17, this plate being thus transversely shift- able on the bed plate 12 and is guided by the flanges 13 and 14. A column or post 18 rises

90

from the base 17 and terminates in a top 19 on which is secured the buck body 20 which has the general shape of an ordinary iron- 95

ing board. The column 18 and its top 19 may be integral with the base plate 17 so that as this base is shifted transversely on the bed plate 12 the buck body will be shifted therewith.

95

The buck body 20 has an outer peripheral flange 21 and an inner flange 22 parallel with and spaced a short distance from the outer

100

flange to leave a channel 23 along the entire periphery of the body. Within the flange 22 is the heating chamber 24 in which steam piping 25 is coiled back and forth. The top of the buck body is covered by a plate 26 having perforations 27 communicating with the channel 23 and other perforations 28 communicating with the heating chamber 24. In the bottom wall of the buck body are the openings 29 and 30 which register with the vertical passageways 31 and 32 through the post or column 18, the upper end of the opening 29 communicating with the heating chamber 24 and the upper end of the opening 30 communicating with a lateral passage 33 connected with the peripheral channel 23.

Within the supporting framework 10 and suspended from the top wall thereof is a blower structure 34 driven by a suitable motor 35, a duct 36 connecting the inlet of the blower with the passageway 32 and a duct 37 connecting the blower outlet with the passageway 31 so that air is blown into the heating chamber 24 and air is withdrawn from the peripheral channel 23 by the blower. The motor 35 may be an electric motor supplied with current through a cable 38 under the control of a switch 39 which may be a mercury switch as indicated at Figure 2.

In order to maintain connection of the chamber 24 and channel 23 with the blower during the different positions of adjustment of the buck structure on the bed plate 12, the base plate 17 has longitudinal parallel channels 40 and 41 in its underside which overlie and are always in register and communicating with the ducts 36 and 37 communicating with the inlet and outlet respectively of the blower, as best illustrated in Figure 3, the lateral adjustment of the buck structure being limited by the extent of the channels 40 and 41, which at one end communicate with the passageways 32 and 31 which lead respectively to the peripheral channel 23 and the heating chamber 24 of the buck body.

As best shown in Figures 4, 7, and 8, the buck structure has a padding P which comprises preferably an outer layer 42 of material such as muslin, and a layer 43 of felt disposed directly under the muslin, and several lower layers 44 of more porous fabric. This padding is held in place on the buck body by means of a clamp frame 45 and covers the perforated plate 26. With this arrangement, when air is blown into the chamber 24 by the blower, the air will be heated by contact with the steam piping and will flow upwardly through the perforation 28 and the porous layers 44 of the padding and will encounter the more impervious layers 42 and 43 whose resistance to the flow of air therethrough will cause them to be deflected upwardly or ballooned. The air which escapes through the padding layers 42 and 43 is hot and dry. The greater part of the air

which does not escape through the padding will find its way back to the blower through the porous layers 44 of the padding and the perforations 27 and channel 23 connected with the blower inlet. The blower capacity is sufficient to compensate for the escape of air through the padding and the blower maintains a constant circulation of air which is heated on its passage through the chamber 24. The purpose of the air circulation and the ballooning action will be referred to more in detail hereinafter.

The ironing head 46 may have the same shape as the buck, and is supported from the front end of arm 47 and 48 connected by a cross beam 49. These arms are mounted on the ends of a shaft 50 journaled in the bearing hubs 51 forming part of the framework 10, and the arms can thus be swung to carry the ironing head toward and away from the stationary buck. To make the engagement of the ironing head with the buck more or less yielding, the arms 47 and 48 have fulcrum lugs 52 engaging in grooves 53 on the head, studs 54 extending from the head and through the arms carrying springs 55 which are yieldably held against the arms by the washers 56 which are adjustable on the studs by means of nuts 57.

The arms 47 and 48 support a pin 58 and between the arms this pin forms a hinge connection for the upper member 59 of the upper toggle link 60 whose lower member 61 is adjustably connected with the upper member by a turn buckle screw 62. By means of this screw the length of the upper toggle link can be readily adjusted. At its lower end this upper link is hinged to the upper end of the lower toggle link 63 by a pin 64, the lower toggle link being hinged at its lower end on the pin 65 supported on the framework 10.

A frame 66 is pivoted at its rear end on a pin 67' supported on the framework 10 and at its front end carries a weight 67 which is connected by rods 68 with ears 69 extending from the ends of the arms 47 and 48, the force of the weight tending to swing the arms to raise the ironing head above the buck to the normal position shown in Figure 1.

Lowering of the ironing head supporting frame automatically controls the connection of the blower driving motor 35 in circuit.

The tube of the mercury switch is pivoted on a bracket 70 which may be mounted on the supporting frame 10 and a lever 71 extending from the tube has a counterweight 72 which is engaged by an arm 73 when the toggle structure is deflected to swing the ironing head downwardly, the arm being mounted on one of the head supporting arms. The mercury tube will then be tilted to cause closure of the motor circuit and operation of the blower. Upon collapse of the toggle

structure and upward swing of the ironing head, the arm 73 will be withdrawn from the counterweight which can then swing the mercury bulb to effect disconnection of the motor circuit. The circulation of air through the buck structure is thus automatically started when the ironing head is brought into operative engagement with the buck structure.

The ironing head may also be heated as by steam piping 74 which is connected by means of hinge couplings 75 and 76 with the steam supply piping 77 and 78 extending concentric with the axis of the hinge shaft 50 for the ironing head supporting framework. Flexible leads 79 and 80 connect this supply piping with the piping coils 25 within the buck structure so that adjustment movement of the buck structure will not be interfered with and the steam supply to the buck structure will be maintained.

Referring to Figure 2, the toggle structure operating mechanism comprises a cylinder structure C having a head 81 from which extends the rear cylinder 82 and the front cylinder 83. The piston 84 in the rear cylinder is connected by a rod 85 with the lower toggle link 63 by the pin 86, while the piston 87 of the front cylinder is pivotally anchored by its rod 88 to a bracket 89 secured to the front wall of the frame work 10. The various valves for controlling the flow of air under pressure to and relief of the air from the cylinder structure are mounted within a panel frame S at the front part of the machine with their operating levers in position to be readily manipulated by the operator.

To support part of the garment or other work to be ironed, panels or shelves 90 and 91 may be provided and these may be secured to the underside of the buck body as indicated in Figures 1 and 3. A clamping frame 92 (Figure 5) is also preferably provided and may be pivoted in lugs 93 and 94 on the underside of the panel 91 with the frame extending around the panel, and springs 95 are provided which tend to swing the upper leg of the clamp against the adjacent end of the buck padding.

Describing now the operation of the machine, as for example, for ironing shirt sleeves, the operator first lays and smooths out the sleeves on the buck padding with the cuffs extended beyond the end of the padding, and then applies the clamp 92 to secure the ends of the sleeves as indicated in Figure 3. With the sleeve ends thus secured, the operator may then stretch the sleeves to get them smoothly aligned on the buck. She then shifts the buck structure so that the sleeves between the cuffs and the shoulder seams of the shirt will be in position to be engaged by the ironing head when it is brought down. She then opens the valve necessary for the air flow to actuate the pneu-

matic structure C to move the toggle structure to swing the ironing head down. When the ironing head starts to swing down, the switch 39 will automatically connect the blower motor in circuit, and, by the time the ironing head gets into the proper position, heated air will be circulating through the buck body and the upper layers of the padding will be ballooned out into engagement with the shirt sleeves through which the hot, dry air escaping through the balloon padding upper layers will then pass to dry the sleeves and subject them to a yielding ironing pressure, the comparatively soft ballooned padding applying this pressure uniformly to the sleeves without any excess pressure against parts of the sleeve such as the seams. During all the time that the ironing head is down, the blower is operating to subject the work to the hot, dry air, and by means of the passages 40 and 41 the blower remains in communication with the buck body passageways and chamber for any positions of adjustment of the buck structure relative to the ironing head. Separate machines are preferably provided for ironing the shirt body, the neck band or the cuffs. The improved machine can of course be used for general ironing purposes, but with the adjustable buck structure it can be quickly and readily adapted for the selective ironing of sleeves or other garment parts.

It is to be understood that although one practical and efficient embodiment of the features of the invention has been shown and described, changes and modifications may be made without departing from the scope and principles of the invention; therefore, it is not desired to be limited except as will be necessitated by the prior art.

What is claimed is:

1. In an ironing machine of the class described, the combination of a stationary support, a buck structure on said support comprising an ironing body and a supporting base therefor, an ironing head mounted on said support for movement into ironing cooperation with said buck structure body, said buck structure body having an air chamber provided with an inlet and an outlet, a padding secured around the sides of said buck structure and overlying said chamber, a blower within said support having outlet and inlet passageways extending through said support, and extended outlet and inlet passageways through the buck structure base connected at one end with the inlet and outlet respectively of said chamber, means adapting said buck structure for transverse adjustment on said support for positioning only a desired part of an article on said padding for engagement by said ironing head, said extended passageways remaining in communication with the outlet and inlet respectively of said blower during any adjustment move-

ment of said buck structure, said blower circulating air under pressure through said chamber to raise or cause ballooning of said padding whereby to apply the article on said padding with uniform pressure against the ironing head.

- 5 2. In an ironing machine, the combination of a stationary support, a buck structure on said support comprising an ironing body and 10 a supporting base therefor, an ironing head mounted on said support for movement into ironing cooperation with said buck structure body, said buck structure body having a fluid chamber provided with an inlet and an 15 outlet, a fluid inlet passage and a fluid outlet passage to said stationary support, there being extended inlet and outlet passageways between said buck structure and support connecting the inlet and outlet passageways to 20 said support with the inlet and outlet of said fluid chambers, means adapting said buck structure for transverse adjustment on said support for positioning only a desired part of an article on said buck structure for engagement by said ironing head, said extended passageways remaining in communication with said support passageways and the fluid chamber inlet and outlet during any adjustment 25 of movement of said buck structure on said support.

- 30 3. In an ironing machine, the combination of a stationary support, a buck structure on said support having a fluid chamber below its ironing surface, an ironing head mounted 35 on said support for movement into ironing cooperation with said buck structure, means adapting said buck structure for transverse adjustment on said support for positioning only a desired part of an article on said buck 40 structure for engagement by an ironing head, said support having fluid inlet and outlet passageways and said buck structure having fluid inlet and outlet passageways for the fluid chambers therein, there being trans- 45 mission passageways between and defined by said support and buck structure for retaining communication between said support inlet and outlet passageways and buck structure inlet and outlet passageways during any 50 adjustment of movement of said buck structure.

- 55 4. In an ironing machine of the class described, the combination of a stationary support, a buck structure on said support, an ironing head mounted on said support for movement into ironing cooperation with said buck structure, means adapting said buck structure for transverse adjustment on said support for positioning only a desired part 60 of an article on said buck structure for engagement by said ironing head, a fluid circulating device mounted on said support and said support having fluid inlet and outlet passages connected with said device, said buck structure having a fluid chamber there-

in and there being extended inlet and outlet passageways for said chamber through said buck structure for communicating with the support inlet and outlet passageways during any adjustment of movement of said buck 70 structure on said support whereby the connection between said fluid circulating device and said chamber is at all times maintained.

- 75 5. In an ironing machine, the combination of a stationary support, a buck structure on said support, an ironing head mounted on said support for movement into ironing co- 80 operation with said buck structure, means adapting said buck structure for transverse adjustment on said support for positioning only a desired part of an article on said buck structure for engagement by said ironing head, a padding on said buck structure, said buck structure having a fluid chamber below 85 said padding provided with a fluid inlet and a fluid outlet, a fluid circulating device mounted on said support and having an inlet and an outlet terminating below said buck structure, said support and buck structure having extended passageways for maintaining connection between said circulating device inlet and outlet and said fluid chamber inlet and outlet during any adjustment of movement of said buck structure on said support, said device circulating the fluid 90 under pressure through said chamber and against said padding to raise and cause ballooning of said padding to apply the article thereon in uniform pressure against the ironing head.

100 In testimony whereof, I have hereunto subscribed my name at Chicago, Cook County, Illinois, this 13 day of December, 1929.
